FITTING CANVAS FOR FUR GARMENTS
OR THE LIKE

Abe Fessler, Maplewood, N. J.

Application December 30, 1949, Serial No. 135,961

6 Claims. (Cl. 33—15)

1

This invention relates to new and useful improvements in fitting coats.

More particularly, the present invention proposes the construction of a fitting coat which is adjustable as to size and style and which is to be used by furriers and fur designers to enable them to obtain accurate fitting measurements of a woman for whom a custom fitted fur coat is to be made.

Prior to the present invention, it has been customary for furriers and fur designers to take the measurements of the woman for whom a fur coat is to be made and to make a dummy coat of canvas material in accordance with the measurements and fit the dummy coat on the woman. The actual fur coat was then constructed in accordance with the correctly dimensioned canvas fitted coat. In that manner the expensive fur pelts were not cut or formed into a coat until the exact configuration of the coat had been determined lessening the possibility of spoiling the expensive pelts. However, that method has proven objectionable because the canvas dummy coat can only be used once and is then discarded with a resulting increase in the cost of the completed fur coat.

The present invention proposes to overcome the objection of the prior method of sizing persons for fur coats by providing fitting coats in certain standard sizes and which are adjustable in the shoulders and in girth to meet the requirements of a particular woman's size and which are adjustable as to style by the addition of auxiliary sleeves and collars to meet the customer's style requirements and which after being adjusted as to size and style may then be used to construct the desired fur coat and which can be reused any number of times by varying its size and style to meet the requirements of each individual customer.

An object of the present invention is to construct a fitting coat having a back section and a pair of like but opposed front sections with slide fasteners joining the back and front sections at their adjacent vertical edges in a manner to be opened and adjusted for varying the girth of the coat in accordance with the customer's requirements.

Another object of the present invention proposes forming the fitting coat with shoulders which are openable to be adjusted to the particular inclination or slope of the shoulders of the woman upon which the coat is being fitted.

Still another object of the present invention proposes forming the front sections of the coat,

2

at the neck opening, with forwardly bent revers upon which a collar is removably mounted in a manner to be removed and replaced by collars of different styles.

5 The invention further proposes providing the fitting coat with integral straight sleeves over which auxiliary sleeves of different styles can be slipped together with means for removably retaining the auxiliary sleeves in position so that their appearance with a collar of a given style can be determined.

10 A still further object of the present invention proposes the construction of a fitting coat which is completely adjustable as to size and style without resorting to cutting and which, therefore, can be used over and over again.

15 It is another object of the present invention to construct a fitting coat which once it has been adjusted as to size and style can be utilized by the furrier or fur designer to transform the particular measurements and style requirements to a paper pattern in a manner to be used for cutting the costly pelts from which the fur coat is to be made.

20 25 For further comprehension of the invention, and of the objects and advantages thereof, reference will be had to the following description and accompanying drawings, and to the appended claims in which the various novel features of the invention are more particularly set forth.

30 In the accompanying drawings forming a material part of the present disclosure:

Fig. 1 is a front elevational view of the fitting coat constructed in accordance with the present invention, but with no collar attached.

35 Fig. 2 is a side elevational view of Fig. 1, but with the side opening partially open.

Fig. 3 is a vertical sectional view taken on the line 3—3 of Fig. 1.

40 Fig. 4 is a side elevational view similar to a portion of Fig. 2, but with the sleeve shown in a raised position and with the side opening completely open.

Fig. 5 is an enlarged detailed view of the shoulder portion of Fig. 2.

Fig. 6 is a plan view of Fig. 5, but with the shoulder in its completely open position.

Fig. 7 is an enlarged partial horizontal sectional view taken on the line 7—7 of Fig. 5.

Fig. 8 is an enlarged partial vertical sectional view taken on the line 8—8 of Fig. 3.

Fig. 9 is a partial vertical sectional view taken on the line 9—9 of Fig. 6.

Fig. 10 is a plan view of the shoulder section

with the shoulder pad attached thereto and prior to mounting in the fitting coat.

Fig. 11 is an enlarged partial horizontal sectional view taken on the line 11—11 of Fig. 3.

Fig. 12 is a sectional view of the dummy pocket taken on the line 12—12 of Fig. 1.

Fig. 13 is a front elevational view of the fitting coat similar to Fig. 1, but with a collar mounted in position and with an auxiliary sleeve in position over the regular sleeve.

Fig. 14 is an enlarged sectional view taken through the collar on the line 14—14 of Fig. 13.

Fig. 15 is a bottom plan view of the collar shown applied to the coat in Fig. 13.

Fig. 16 is a bottom plan view of another style collar which can be used with the coat.

Fig. 17 is a perspective view of the auxiliary sleeve shown mounted in position on the coat in Fig. 13.

Fig. 18 is a plan view of Fig. 17.

Fig. 19 is an enlarged partial sectional view taken on the line 19—19 of Fig. 17.

Fig. 20 is a perspective view similar to Fig. 17, but illustrating another type of sleeve which can be used with the fitting coat.

The fitting coat, according to the present invention, includes a back section 30 and a pair of like but opposed front sections 31. The sections 30 and 31 of the coat are formed of the usual canvas material employed by furriers and fur designers for obtaining the measurements of a person for whom a custom fur coat is to be made. In securing together the sections 30 and 31 of the garment, the usual arm holes are left in the top of the garment and straight sleeves 32 are secured (as will be explained hereinafter) in position in those arm holes. From Figs. 1 and 2 it will be noted that the sleeves 32 carry no cuffs or other decorative materials and that the free edges thereof are bent under and secured in position by stitches 33.

The adjacent vertical slide edges of the back section 30 and the front sections 31 are releasably joined together by slide fasteners 34 having the usual tapes 35 secured to the edges of the sections 30 and 31 by lines of stitches 36, see Figs. 2, 4 and 11. If the fitting coat, as made, properly fits the person being fitted, the sections 30 and 31 will be joined at the sides by the slide fasteners. From Fig. 4 it will be noted that the slide fasteners 34 are extended partially into the tops of the sleeves 32 on the inner sides thereof. Secured to the vertical side edges of each of the front sections 31 by the same lines of stitches 36 which secure the respective tapes 35 of the slide fasteners 34 in position, there is a gusset 37. As clearly illustrated in Fig. 11, each gusset 37 is secured in position only along one vertical edge thereof and the free edges of the gussets are projected across the back of the slide fasteners 34 and the inner faces of the back section 30. That is the normal position of the gussets 37 when the sections 30 and 31 are joined together by the slide fasteners 34. However, when it is necessary to adjust the girth of the fitting coat either inward or outward, it is merely necessary to completely open the slide fasteners 34, as shown in Fig. 4, and then by means of pin 38, as illustrated in Fig. 3, the free edges of the gussets 37 are secured to the vertical side edges of the back section 30 in accordance with the size requirements of the particular woman being sized. It will be appreciated that extending the slide fasteners 34 partially into the sleeves 32, as shown in Fig. 4, permits girth adjustments to be more

smoothly made to the body of the coat without interference from the sleeves 32 at their points of attachment to the sections 30 and 31.

The adjacent edges of the back section 30 and the front sections 31 at the shoulders, between the neck opening and the arm holes, are releasably connected together by slide fasteners 39, see particularly Figs. 5 and 6. The slide fasteners 39 have the usual tapes 40 secured to the edges of the shoulder portions of the sections 30 and 31 by lines of stitches 41. The slide fasteners 39 are preferably of the non-separable type and to provide greater movement of the shoulder portions of the sections 30 and 31, in the open condition of the slide fasteners, those slide fasteners 39 are extended beyond the outer edges of sections 30 and 31 which define the tops of the arm holes, see Figs. 1, 2 and 5. Thus, when the slide fasteners 39 are completely opened, as shown in Fig. 6, greater freedom is given to the shoulder portions of the sections 30 and 31. However, if desired, the shoulder portions of the sections 30 and 31 could be joined together by the separable type slide fasteners permitting the shoulders of 20 the sections to be completely separated in the open condition of the slide fasteners.

Positioned beneath each of the shoulder portions of the fitting coat there is a substantially triangularly shaped shoulder section 42. The shoulder sections 42 are made of the same material used for making the sections 30 and 31 of the coat and to give the sections 42 greater shape they are preferably formed of opposed like half sections stitched together along a line 43 located 30 centrally beneath the slide fasteners 39, see Figs. 6 and 10. The apexes of the triangularly shaped shoulder sections 42 are directed inward with the bases thereof directed outward. The corners of the shoulder sections 42, adjacent the bases 35 thereof, are secured to the inside faces of the back section 30 and the front sections 31 by lines of stitches 44, see particularly Fig. 8.

Mounted on the bottom face of each of the shoulder sections 42, there is a shoulder pad 45. The shoulder pads 45 are secured in position by 45 a substantially arcuate line of stitches 46 so that the outer edge portions of the pads project slightly beyond the free outer edges of the shoulder sections 42, as shown in Fig. 10, and into the top portions of the sleeves 32, as shown in Fig. 9, for shaping and lifting the top portions of the sleeves. The shoulder pads 45 are of conventional construction and further constructional details of the pads will not be given in the present specification as such details form no part of the present invention.

In addition to the slide fasteners 39 which releasably secure together the edge portions of the shoulder portions of the sections 30 and 31, means is provided for releasably securing those shoulder portions to the shoulder section 42. That releasable securing means is characterized by a pair of downwardly and outwardly inclined tapes 47 secured to the top face of each of the shoulder sections 42 on opposite sides of the shoulder pads 45 by means of stitches 48. Mounted in spaced positions along the lengths of the tapes 47 there is a plurality of socket-type fastener elements 49. Secured to the inner faces of the shoulder portions of the sections 30 and 31, there are similar tapes 50 matching the downward and outward inclination of the tapes 47. The tapes 50 are secured to the shoulder portions of the coat sections 30 and 31 by lines of stitches 51. Mounted on the tapes 50 there are the comple-

mentary post-type fastener elements 52 which are engageable with the socket-type fastener elements 49 of the tape 47. Thus, when the fastener elements 49 and 52 are engaged they function to retain the shoulder section 42 and the shoulder pad 45 in proper position within the shoulder portion of the coat.

Returning again to the sleeves 32, it will be apparent that the bottom edge portions of the material defining the arm hole of each sleeve, on opposite sides of the slide fastener 34, are secured to the corresponding edge portions of the coat sections 30 and 31 by lines of stitches 53, see Figs. 3 and 8. Thus, the sleeves are attached to the sections 30 and 31 from one attached corner of the shoulder section 42 to its other attached corner except for the interruption by the slide fasteners 34. The top edge portions of the material defining the arm hole of each sleeve are secured to the corresponding edge portions of the shoulder sections 42 by lines of stitches 54, see Fig. 9, so that the shoulder portions of the sections 30 and 31, between the attached corners of the shoulder section 42, are free of any connection with the sleeves 32. Thus, when the slide fastener 39 is completely opened and the fastener elements 49 and 52 are disengaged, the shoulder portions of the sections 30 and 31 can be folded outward, as shown in Fig. 6, freeing the shoulder section 42 and the attached shoulder pad 45 to be adjusted. In the normal size for which the coat is made, the fastener elements 49 and 52 will be engaged and the slide fastener will be closed. However, if it is necessary to adjust the position of the shoulders of the garment to suit the needs of a particular customer, both the slide fastener 39 and the fastener elements 49 and 52 are disengaged so that the shoulder portions of the sections 30 and 31 will be free to be adjusted as required and then be secured in their adjusted positions to the shoulder section 42 by the conventional straight pins. This adjustment is not interfered with by the stitches 44 as the lifting of the free portions of the shoulder portions of the sections 30 and 31 to the desired adjusted position will similarly lift the stitches 44 and cause an upward bending of the shoulder sections 42 along substantially horizontally extended lines above the lines of stitches 44.

Secured to the inner top corners of the front sections 31 of the fitting coat, there is a lining layer 55, see particularly Fig. 14. The lining layer 55 permits the inner top corners of the front sections 31 to be folded outward to form revers 56 to which a collar 57 can be removably attached, as shown in Fig. 13. Means is provided for releasably attaching the collars 57 to the revers 56 so that the collars can be removed and replaced by a different collar of a different design; for instance the collar 57' shown in Fig. 16. The collar 57 of Figs. 13 and 15 and the collar 57' of Fig. 16 are the same except for differences in design. The releasable attaching means for the collars comprises a single snap fastener element 58 secured to the inside faces of each of the sections 31 at substantially the bottom ends of the revers 56. A pair of like snap fastener elements 59 are mounted on the revers 56 at the top ends thereof, see particularly Fig. 1. Mounted on the back face of the collar 57 and the collar 57' there are complementary snap fastener elements 60 which engage the snap fastener elements 58 and 59 and releasably retain the respective collar 57 or 57' in position. Only

two styles of collars have been illustrated on the drawings, but it is appreciated that many collars can be provided in a great number of different styles for use with each coat.

Likewise, sleeves 61, see Figs. 13 and 17, of different styles can be engaged in position over the sleeves 32. The sleeve 61 differs from the sleeves 32 in that it has wide cuff 62. In Fig. 20 a sleeve 61' of still another design is illustrated which has a narrow wristlet 62', which may be interchangeably used with the sleeve 61.

Means is provided for releasably attaching the sleeves 61 or 61' in position over the sleeves 32. That attaching means comprises a narrow projecting strip 63 which extends from the top of each of the sleeves 61 or 61'. The strip is arranged to be inserted between the adjacent faces of the shoulder section 42 and the shoulder portions of the coat sections 30 and 31. Each strip 63 carries a spaced pair of post-type snap fastener elements 64, see particularly Figs. 18 and 19, which are releasably engageable with a spaced pair of complementary socket-type fastener elements 65 mounted on the shoulder sections 42, see Figs. 6 and 9. The construction is such that a pair of like auxiliary sleeves, of a design different from the sleeves 32, may be mounted in position over the sleeves 32 or auxiliary sleeves of different designs may be engaged over each of the sleeves 32 permitting a comparison to be made and the desired sleeve style to be selected.

The front sections 31 of the coat are provided with dummy pockets 66 for completing the appearance of the fitting coat. On the drawing, the pockets 66 are illustrated as being of the "slash" or military type, but such showing is merely illustrative and any other type of pocket may be provided. Details of the formation of the dummy pocket 66 are illustrated in Fig. 12. The pockets 66 are formed by providing the front sections 31 of the fitting coat with downwardly and outwardly inclined I-shaped cuts with the material 67 on one side of the cut being folded backward and secured to another piece of material 68 by stitches 69. Likewise, the material 70 of the front section on the other side of the I-shaped cut is doubled back upon itself and secured to another strip of material 71 by a line of stitches 72. The adjacent top and bottom edges of the strips of material 68 and 71 are preferably secured together by lines of stitches not shown.

The manner of using the fitting coat of the present invention is as follows:

The custom furrier or fur designer stocks a supply of the fitting coats, preferably at least one in each general size classification. Thus, a customer to be fitted for a custom fur coat dons one of the fitting coats which, in general, is her size. However, as extremely few women conform rigidly to one size throughout their configuration the girth and the shoulder height of the donned fitting coat can be adjusted as previously indicated to meet the requirements of the customer being sized.

Moreover, while the basic line or style of a particular fur coat may be suitable to a great majority of women, each desires a particular collar style and a particular sleeve style which she feels is particularly appealing to her. The interchangeable sleeves and interchangeable collars permit each woman to select the particular collar and sleeve style which appeals to her.

After sizing and styling of the fitting coat has been completed the adjusted measurements can be quickly and easily transferred to a paper pat-

tern which can then be used for cutting the costly pelts from which the final coat is to be made without danger of spoiling any of the furs.

While the features of the present invention have been shown applied to a loose fitting or "box" coat, it will be appreciated that such showing is by way of illustration only and that those features are equally well adapted for use in a fitted coat or any other type of coat without departing from the scope of the present invention.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a fitting coat having a back section and a pair of like but opposed front sections with adjacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of said fasteners, stitches securing the ends of the base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections.

2. In a fitting coat having a back section and a pair of like but opposed front sections with adjacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of said fasteners, stitches securing the ends of the

base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections, and shoulder pads secured to the bottom faces of said shoulder sections.

3. In a fitting coat having a back section and a pair of like but opposed front sections with adjacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of said fasteners, stitches securing the ends of the base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections, said first-mentioned fasteners being slide fasteners.

4. In a fitting coat having a back section and a pair of like but opposed front sections with adjacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of

said fasteners, stitches securing the ends of the base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections, said second mentioned fasteners comprising complementary lines of downwardly and outwardly inclined rows of fastener elements on the adjacent faces of said shoulder sections and the shoulder portions of the front and back sections.

5. In a fitting coat having a back section and a pair of like but opposed front sections with adjacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of said fasteners, stitches securing the ends of the base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections, slide fasteners releasably securing together the adjacent side edges of the back and front sections, vertically elongated gussets each secured along one vertical edge to the inner faces of one of the back sections or the front sections to one side of said slide fasteners, so constructed and arranged that when said slide fasteners are opened the other vertical edges of said gussets can be adjustably pinned to the other of the back sections or the front sections on the other side of said slide fasteners.

6. In a fitting coat having a back section and a pair of like but opposed front sections with ad-

jacent side edges and adjacent shoulder portions having adjacent top edges, said side edges and said top edges being extended in opposite directions from armhole openings formed in said back section and said front sections, fasteners releasably securing together the adjacent top edges of the sections, a triangularly shaped shoulder section positioned within each of said shoulder portions of the coat with their base sides facing outward and flush with the edges of said sections defining the upper halves of said armhole openings, said shoulder sections having the ends of their base sides located at diametrically opposite sides of the armhole openings on a line extended horizontally across the center of said armhole openings and spaced equally on opposite sides of said fasteners, stitches securing the ends of the base sides of said shoulder sections to the inner faces of the back and front sections, fasteners releasably securing together the adjacent faces of said shoulder sections and the shoulder portions of the front and back sections on opposite sides of said first-mentioned fasteners, sleeves having top openings conforming in size to the size of the armhole openings, stitches securing the lower halves of the material of said sleeves defining their top openings to the material of the front and back sections defining their armhole openings below the level where said first-mentioned stitches secure the ends of the base sides of said shoulder sections to the front and back sections, and stitches securing the upper halves of the material of said sleeves defining their top openings to the base sides of said shoulder sections, slide fasteners releasably securing together the adjacent side edges of the back and front sections, vertically elongated gussets each secured along one vertical edge to the inner faces of one of the back sections or the front sections to one side of said slide fasteners, so constructed and arranged that when said slide fasteners are opened the other vertical edges of said gussets can be adjustably pinned to the other of the back sections or the front sections on the other side of said slide fasteners.

ABE FESSLER.
